CLAIM

The ornamental design for a pacifier for babies, as shown and described.

DESCRIPTION

FIG. 1 is a front elevation view of a pacifier for babies showing the new design.

FIG. 2 is a rear elevation view thereof.

FIG. 3 is a right side elevation view thereof.

FIG. 4 is a left side elevation view thereof.

FIG. 5 is a top plan view thereof.

FIG. 6 is a bottom plan view thereof; and,

FIG. 7 is a top, front, right perspective view thereof.

In the drawings, the broken lines depict portions of the pacifier for babies that form no part of the claimed design.
